BALLPOINT PEN

Alan E. Sherman, Olivette, Mo., assignor to Ritepoint Pen and Pencil Company, St. Louis, Mo., a corporation of Missouri

Filed Apr. 8, 1963, Ser. No. 74,327

Term of patent 14 years

(Cl. D74—17)

FIG. 1

FIG. 2

FIG. 4

FIG. 3

FIG. 5

FIG. 1 is a front elevational view of a ballpoint pen embodying my new design;

FIG. 2 is a side elevational view thereof;

FIG. 3 is a top plan view thereof;

FIG. 4 is a bottom plan view thereof; and

FIG. 5 is a transverse sectional view taken along line 5—5 of FIG. 2.

I claim:

The ornamental design for a ballpoint pen, substantially as shown.
